UNITED STATES PATENT OFFICE.

MANUEL F. DE SOUZA, OF SPRINGFIELD, ILLINOIS.

VALVE FOR STEAM-PUMPS.

SPECIFICATION forming part of Letters Patent No. 225,575, dated March 16, 1880.

Application filed December 17, 1879.

To all whom it may concern:

Be it known that I, MANUEL F. DE SOUZA, of Springfield, in the county of Sangamon and State of Illinois, have invented certain new and useful Improvements in Valves for 5 Steam-Pumps; and I do hereby declare that the following is a full, clear, and exact description thereof, reference being had to the accompanying drawings, and to the letters of 10 reference marked thereon, which form part of this specification.

My invention relates to steam-pumps; and it consists in the peculiar construction and arrangement of the steam-chest and valve as 15 will be hereinafter more fully pointed out, and set forth in the claim.

In order to enable others skilled in the art to which my invention appertains to make and use the same, I will now proceed to describe 20 its construction and operation, referring to the annexed drawings, in which—

Figure 1 is a side; elevation Fig. 2, a central vertical section, showing the exhaust-ports in dotted lines; and Figs. 3 and 4 are 25 details of parts of my invention.

A represents the steam-cylinder. B is the water-cylinder, with air-chamber C on top. E is the steam-chest on top of the steam-cylinder A, with steam-inlet pipe D and an exhaust, F, on each side.

On each side of the water-cylinder B are discharge-opening G and suction-opening H for the water.

I is the bed of the machine. K is the piston-rod, on which is secured the shipper J, working on the valve-rod M, between tappers L L, secured thereon.

On the valve-rod M, within the steam-chest, 40 is the steam-valve, which consists of a hollow sleeve, O, with four cylindrical parts or rings, O' O² O³ O⁴, fitting the bore of the steam-chest, and all made in one piece, the valve being movable on the rod. At each end of this movable valve is fastened an auxiliary 45 valve on the rod, said valves being marked R R', and are at such distances apart as to admit of a certain movement of the movable valve.

Leading from the steam-chest E are ports

Y Y' into the cylinder, and in the under face 50 of the steam-chest is a channel, W W', with a central passage, V, leading from steam-chest and end passages, x x', into the chest, back of valves R R'.

Steam enters through the pipes D into the 55 chest and into the space between the parts O² O³ of the movable valve, as seen in Fig. 2, and passes from the interior, through the passage or port V and groove W', through the port x', back into the chest, between the auxiliary 60 valve R' and the chest-head. It then passes through holes p in said auxiliary valves to the space r, between R' and part O⁴, holding the entire movable valve as far to the left as the stop-pin a, projecting through hole b, will 65 permit, leaving a space between O⁴ and R', to permit the valve-rod, with the valves R R', to be moved to the right under the shipper J, and uncover the port x, and allow steam to enter from the channel W, between the auxiliary valve R and the chest-head, and to pass through the holes in said valve and shift the movable valve to the right.

The shipper reversing moves the valve-rod 70 and auxiliary valves, uncovering the port x', and closing x, and so continues.

The auxiliary valves R R' are counterbored on their faces to allow the steam, after passing through the holes p, to expand and act on the whole face of the movable valve.

While steam is passing along the groove W', through port x', it is also passing from the center space through the port Y, on the left, to the steam-cylinder, and, moving the piston to the right, exhausts through the port 85 Y' and exhaust-ports into the space between the parts O³ and O⁴, and into either exhaust-opening F, as may be convenient. Then, when the piston-head is at the end of its stroke to the right the shipper has moved the valve-rod 90 M and auxiliary valves R R' to the right, letting steam through the port x, to work the valve, as above stated.

Having thus fully described my invention, what I claim, and desire to secure by Letters 95 Patent, is—

In a steam-pump, the valve-rod M, having attached valves R R', with holes p p and cir-

cular spaces r r , and movable valve O , having rings O' O^2 O^3 O^4 , in combination with steam-chest E , provided with stop-pin a , and channel W W' , with central passage, V , and end 5 passages, x x' , all constructed and arranged to operate in the manner and for the purpose set forth.

In testimony that I claim the foregoing as my own I affix my signature in presence of two witnesses.

MANUEL F. DE SOUZA.
